CARTON AND LIKE CONTAINER

Kenneth Bertram James Blakemore,
Hyde, EnglandApplication October 11, 1938, Serial No. 234,464
In Great Britain October 25, 1937

5 Claims. (Cl. 229—22)

This invention relates to cartons and like containers which are constructed from sheet material, for example, from paper or thin cardboard and particularly, although not exclusively, to cartons which are liquid-tight and suitable for use in the vending of milk. Such cartons are being found both economical and hygienic for the retailing of milk; being usable once only.

The invention has for an object to provide an improved construction of carton which is simple and inexpensive in manufacture and possesses advantages over known cartons.

The invention is illustrated by the accompanying drawing, of which:

One form is shown in Figures 1 to 4; Figure 1 being a face view of the creased blank from which the carton is made;

Figure 2 being a similar view of the blank folded;

Figure 3 being a sectional view on the line 3—3 of Figure 2 with the transverse dimensions exaggerated for clearness; and

Figure 4 being a perspective view of the completed carton in its distended condition; whilst

Figure 5 is a diagram showing alternative shapes of blanks.

Referring to Figures 1 to 4, a carton of paper or other creasable sheet material is made from a rectangular piece 11 which has four creases or lines of weakness, one of which 12 is close to and parallel with the side edge 13; another, 14, extends diagonally across the larger part of the piece 11 defined by the line 12, whilst the remaining two lines 15 and 16, extend from a common point 17 in the line 14 perpendicular to the two adjacent sides 18 and 19 respectively, which meet at the end 20 of the diagonal 14. The longitudinal dimension of the piece 11 exceeds by a small amount its vertical dimension, and the larger part defined by the line 12 is square. The line of weakness 16 bisects the whole of the side 19 and the line 15 meets the side 18 a little above its mid point. In folding the blank to the position shown in Figure 2, it is folded about the diagonal 14, and the two triangular parts adjacent the end 20 are turned so that the corner 20 is coincident with the wing corner 21, with the wing corner 22 disposed coincident with the lower end of the line of weakness 12. In the flattened condition the two halves of each of the sides 18 and 19 are stuck together after the loose insert or former, indicated by broken lines at 23, is positioned on the blank 11. The former 23 has a line of weakness coincident with the diagonal 14 and has its shorter edges, remote from its

5 folding line, disposed a short distance away from the corresponding edges of the blank 11, so that as pressure is applied to the blank 11 to stick the halves of the sides together the blank will be offset, to a small degree, just above the adhering surface. The effect of the offsetting is clearly shown in Figure 3. The carton is completed, after removing insert, by sticking the flap 24 and the corner 25 to the outer margin of the edge 26 of the blank 11, and by subjecting the blank to a wax bath which renders the material impervious to milk or other liquids. The effect of the offset caused by the former 23 results in the stuck surfaces of the edges 18 and 19 being protected by a bead of wax which is indicated at 27 in Figure 3; also the offsetting simplifies the waxing of the carton inasmuch as the internal surfaces of the side walls are separated. A filling and outlet opening is left at the upper end of the carton by cutting away the upper corner, for example along the line 28.

Figure 4 shows the carton in its distended position in which it is in the form substantially of a triangular pyramid; the line of weakness 14 extending along the base 29 from one corner thereof and along the side 30 opposite said corner to divide the base 29 and side 30 centrally, whilst the lines of weakness 15 and 16 extend obliquely from the other corners of the base to a common point in the line 14 on the rear side 30. The junction between the base 29 and the creased side 30, and the junction between the latter and the two uncreased sides 31 and 32 are not sharply defined but are rounded and blend gradually.

35 The two flanges 33 and 34 by which the lower edges of the sides 31 and 32 are united to the base 29 can be reinforced by comparatively rigid strips 35 and 36 disposed over said flanges either at the inside or outside. The reinforcing strips 40 are preferably made of thin strips of wood which are cut across the grain so that the supporting edges of the strips are end-grained. In the case described these reinforcing strips are shown at the inside of the flanges.

45 By constructing the carton from the blank shown in Figure 1, the junction between the uncreased sides 31 and 32 is normal to the base 29. However, if desired, the blank may be so shaped that the resulting carton will have this junction at an angle to the base either sloping away from or towards the opposite, creased, side. This and other possibilities in respect of the shape of the blank will be clear from Figure 5, which is essentially diagrammatic. In general, the blank is 50 formed from a six-sided figure ABCDEF, sym-

metrical about its diameter AD. It will readily be seen that the line AB (or AF) represents the front edge of the carton. Again BC and CD, with DE and EF, are the base lines, being all equal to one another when the matter is considered diagrammatically; that is to say, ignoring the necessity for turn-overs and so on. The angle ABC determines the slope of the front edge; the angle CDE determines the front base angle; in other words, the spread between the sides. Finally, the length CE determines the width of the carton across the rear edge. The figure shows in broken lines several ways in which the blank can be varied. In particular, it is noted that the lines BC and CD can become one straight line, BCD thus giving a four-sided cutting blank. Such forms reduce or eliminate waste when the blanks are being cut from a reel.

A carton in accordance with the invention can be distended from its flattened condition by hand or can be distended by the action of filling. This latter method is of particular advantage where the carton is to be filled with a liquid to be consumed, for it will be appreciated that the liquid comes into contact with only a very small quantity of air, whereas with the milk cartons as at present in use, this is not the case.

The opening at the top of the carton can be closed by any known or convenient means, for example by a length of channeled metal strip. Also the margin of the opening can be folded over when flattened out.

Cartons or like containers in accordance with the invention can be packed in stacks or bundles before being filled and, when filled, can be stored or stacked with a minimum amount of waste space. Also, when filled, they can conveniently be arranged for display purposes about a centre, and as the apices of several cartons can be disposed close to one another, several can be held in the hand at one time.

What I claim is:

1. A one-piece carton having a triangular base, two triangular sides, and a triangular rear, with a line of weakness extending from the apex of the carton centrally down the rear and along the base, and two other lines of weakness extending from the two rear base corners to a common point in the central line of weakness, the carton having a sealed joint along the edge common to the two sides, and having sealed joints between the sides and base, said sides having portions which extend below the plane of the base and are united to the base by two depending flanges integral with the base.

2. A one-piece carton having a triangular base, two triangular sides, and a triangular rear, with a line of weakness extending from the apex of the carton centrally down the rear and along the base, and two other lines of weakness extending from the two rear base corners to a common

point in the central line of weakness, the carton having a sealed joint along the edge common to the two sides, and having sealed joints between the sides and base, said sides having portions which extend below the plane of the base and are united to the base by two depending flanges integral with the base, the depending flanges being reinforced by wooden strips cut across the grain.

3. A one-piece carton having a triangular base, two triangular sides, and a triangular rear, with a line of weakness extending from the apex of the carton centrally down the rear and along the base, and two other lines of weakness extending from the two rear base corners to a common point in the central line of weakness, the carton having a sealed joint along the edge common to the two sides, and having sealed joints between the sides and base, the sides being united to the base by flanges depending from the base, wherein just above their union with the flanges of the base the sides are offset to a small degree so that when the carton is subjected to a wax bath, a bead of wax will extend immediately over the junctions between the sides and the base.

4. A carton having a triangular base, two triangular side walls, and a triangular rear wall, a filling and emptying orifice at the apex of the carton, with a folding line extending from said orifice centrally down the rear wall and continuing centrally across the base to the opposite corner thereof, and two other folding lines extending from the two rear base corners to a common point on said central folding line on said rear wall, the rear wall being integrally joined with the side and bottom walls and joined thereto in operative position along rounded corners, and the edge between said side walls and the edges between the side walls and said bottom wall being adhesively joined together, the edges between said side walls being defined relatively sharp.

5. The method of producing a carton which consists in folding a single rectangular sheet of material substantially symmetrical about a diagonal, inturning the sheet at one corner which is at the end of the diagonal, so that this corner is coincident with the two wing corners and lies between them with the two edges of the sheet immediately adjacent said corner lying in a common plane, adhesively joining the edges of the other two sides of the sheet adjacent the opposite end of the diagonal and adhesively joining the edges of the two halves of each of the inturned sides with the edges of the adjacent two halves of each of the two wing sides in face contacting relation, cutting off a portion of the container adjacent the said opposite end of said diagonal to form a filling and emptying opening for said container, and spreading said wing sides.
